(57) **CLAIM**

The design for the multi-functional self-propelled farm tractor, as shown.

DESCRIPTION

FIG. 1 is a side view of the multi-functional self-propelled farm tractor;

FIG. 2 is a front view thereof;

FIG. 3 is a top view thereof; and,

FIG. 4 is a top view of an alternative embodiment thereof.
The broken line showing is for illustrative purposes only and
forms no part of the claimed design.
